FLUID HEAT EXCHANGE APPARATUS

Howard J. Kerr, Westfield, N. J., assignor to The Babcock & Wilcox Company, Newark, N. J., a corporation of New Jersey

Application April 30, 1938, Serial No. 205,229

9 Claims. (Cl. 122—488)

This invention relates to fluid heat exchange apparatus, and it is exemplified in improvements in water tube steam boilers whereby the safe steaming capacities of such boilers are increased.

In the art of steam generation progressively greater efficiencies have been attained by the utilization of higher operating pressures. Progressively higher rates of steam generation have also been a factor in the development of the art. Both factors have demonstrated the importance of securing efficient steam and water separation without increasing the steam and water separating space in the drums. If this space were increased in accordance with prior art teachings, greater drum diameters would be necessary and, for the pertinent high pressures (of the order of 1000-2000 lbs. per sq. inch) the provision of drums of the necessarily greater diameter would result in excessive increases in drum wall thickness. They would be excessive from many standpoints including manufacturing limitations and cost limitations. The present invention provides improvements which effect a safe degree of steam and water separation at high pressures and high capacity operation without necessitating drums of excessive diameter.

The high capacities of modern steam boilers have also made it particularly difficult to insure continuous supply of dry steam without excessive drum capacity. The high heat input into the furnace wall tubes under such high capacity conditions causes those tubes to produce high velocity discharges of steam and water into the drum, and the natural tendency of this condition is to keep the steam and water mixed within the drum. Furthermore, the necessity of providing adequate ligaments in the drum prevents the concentration of the drum connections for such furnace wall tubes. They must be distributed over wide drum areas. This also has an additional tendency to produce high drum turbulence and make steam and water separation increasingly difficult. The present invention overcomes these difficulties, and, in so doing, utilizes the high velocity of the discharges into the drum to promote steam and water separation and render a given boiler capable of supplying dry steam while operating at water levels higher than would otherwise be permissible.

The present invention also provides a means for increasing the safe steaming capacity of a natural circulation steam boiler by minimizing the amount of steam carried down with the water from the drum to the steam generating

tubes, and by increasing the amount of water received by them, through an increase in the boiler circulation rate.

Another object of the invention is to provide improvements which will enable a given water tube steam boiler to operate at maximum capacities by permitting effective operation of the boiler under high water level conditions. To accomplish these results, the invention contemplates the use of centrifugal water and steam separators having whirl chambers each of which is provided with an exit for the separated water limited to the region of the perimeter of the chamber, preferably tangentially. Other objects of the invention will appear as the following description proceeds.

The invention will be described with reference to the accompanying drawings in which certain embodiments of the invention are illustrated.

In the drawings:

Fig. 1 is a vertical section through a three-drum boiler of the bent-tube type, constructed in accordance with the teachings of the invention;

Fig. 2 is a vertical sectional view showing the front drum of the Fig. 1 boiler on an enlarged scale;

Fig. 3 is a detailed sectional view indicating the construction of the illustrative steam and water separator. This view may be considered as taken on the line 3—3 of Fig. 4;

Fig. 4 is a sectional view of the separator taken along a plane at right-angles to the plane of Fig. 3 and on such a section-line as that indicated at 4—4 of Fig. 3;

Fig. 5 is a vertical section taken upon the section-line 5—5 in Fig. 4 and looking in the direction of the arrows;

Fig. 6 is a vertical section of a two-drum type of bent-tube boiler to which the invention is applied in another manner;

Fig. 7 is a vertical section of the steam and water drum of the Fig. 6 boiler, on an enlarged scale;

Fig. 8 is a horizontal sectional view of the Fig. 1 boiler taken approximately on the section-line 8—8 of Fig. 1;

Fig. 9 is a horizontal section taken on the section-line 9—9 of Fig. 6;

Fig. 10 is a vertical section showing a modification of the structure indicated in Fig. 2.

Fig. 1 of the drawings discloses a bent-tube boiler having front and rear upper drums 10 and 12 connected with the submerged drum 14 by the banks of tubes 16 and 18, respectively. The steam generating tubes of the tube bank 18 are

exposed to the heat of the furnace 20, the furnace gases passing over these tubes.

Steam and water is discharged by the tubes 18 into the front drum 10, and water together with some steam from this drum passes through the large diameter circulators 22, and then across the rear drum 12 through the cross-over tubes 24 and 26 into the rear tubes 23 of the boiler. This arrangement permits the use of the pressure differential between the drums 10 and 12 to establish the tubes 28 definitely as downcomers, and with the use of the centrifugal separators 30 interposed in the cross-over tube connections, the discharge through the circulators 22 is relieved of steam, and circulatory advantages are obtained because of the higher density of fluid in the tubes 28 over their full heights. The density of the fluid in these tubes is here compared with the density of the fluid in the tubes 18.

It will be understood that there are a number of the circulators 22 and a corresponding number of the separators 30 disposed longitudinally of the drum 12. The construction of the separators is indicated in Figs. 3 and 4 of the drawings. Each separator consists of a whirl chamber 32, operating independently of gravity to insure steam-free water in the downcomers 28 and thereby increase maximum safe boiler capacity. The cross-over tube 24 is arranged tangentially to the whirl chamber 32 so as to set up a circular flow of water within that chamber. This flow is indicated by the arrow 34 in Fig. 3. In the operation of the whirl chamber, the pressure of the water at its perimeter is substantially greater than the pressure in the center of the chamber, and the pressure of the water is substantially equivalent to the combined velocity of the steam and water entering that chamber from the inlet cross-over tube 24. The pressure at the perimeter of the chamber is always greater than the pressure in the center.

The liquid or water outlet of each whirl chamber 32 is provided in the present instance by the cross-over tube 26 which is arranged at the perimeter of the whirl chamber and preferably tangentially of that chamber. The latter arrangement is indicated in Fig. 3 of the drawings. The water in the whirl chamber outlet 26 will have a velocity substantially equal to the combined velocity of the vapor (or gas) and the water at the tangential entrance 24, whereby a pressure is developed in the water equivalent to this velocity.

The delivery pressure of such steam and water separators may be utilized to lift the water to a higher level or to deliver it against an equivalent out-flow resistance to flow. The advantage of this characteristic is taken in the Fig. 1 embodiment wherein similar separators 40 are arranged to receive the high velocity discharge of steam and water from the wall-tube risers 42. In this instance, the axes of the whirl chambers are arranged horizontally, or longitudinally of the drum 10, and each riser 42 discharges its stream of steam and water at high velocity through the tangential inlet 44 of a whirl chamber 40. The water separated by the action of the whirl chamber passes therefrom through tangential outlet 46 downwardly toward the water space of the drum 10, and, in the event that the water level of this drum is above the bottom of the whirl chamber 40, the delivery pressure will cause the separated water to be delivered, or discharged, from the separating zone against the resistance of the higher water level.

With reference to the steam and water separators 40, it is to be noted that they receive the restricted streams of steam and water mixtures from the wall tubes 50 which are highly heated by reason of their exposure to radiant heat from the furnace 20. These wall tubes 50 are in communication with the risers 42 through the upper wall tube header 52.

In the form of the centrifugal steam and water separator indicated in Figs. 3 and 4 of the drawings the whirl chamber is closed except for the above mentioned steam and water inlet 24, the water outlet 26, and the steam outlet 54. The latter is arranged centrally of the whirl chamber so that the steam may be discharged axially of that chamber. The steam outlet 56 of the horizontally arranged separators 40 are similarly axially arranged.

The vertical baffle plate 60 in the drum 10 gives a higher percentage of solid water through the circulators 22 and, in conjunction with the separators 30, assists in maintaining a reasonably high velocity in the downcomers 28. The amount of water received by the steam generating tubes 18 is thus increased and the boiler therefore caused to have a greater safe steam generating capacity.

Fig. 10 shows an embodiment of the invention similar to that indicated in Fig. 2, but having the water outlet connection 65 for the water chamber 40 directly connected to and discharging into a downcomer as shown.

Steam vented from the separators 30 through the outlets 54 passes into the steam space of the drum 12 and thence through the steam scrubbers 62 to the steam offtake 64. From this offtake it passes to a superheater 66, the relation of the superheater tubes to the remainder of the tubes of this boiler being indicated in Fig. 8 of the drawings. The furnace gases pass over the steam generating tubes 18 and then over the tubes of the superheater 66 through the first gas pass 68 defined by the boiler setting wall 70 and the baffle 72. In passing over some of the tubes of the bank 16 at the exit of the gas pass 68 the gases turn into the second gas pass 74, pass back across the tubes 16, and then make a second turn through a third gas pass 76. The tubes in the last two gas passes are separated from the gas flow equalization chamber 80 by a baffle 82 which is shown in section in Fig. 1 of the drawings. From the outlet of the gas pass 76 furnace gases may pass over an economizer, and thence to an air heater.

Fig. 7 shows the arrangement of the illustrative densifier or steam and water separator 200 when used for primary separation of water and steam in the drum 202 of the type of boiler indicated in Figs. 6 and 9 of the drawings. The water and steam mixture discharged into the drum from the steam generating tubes 204, 206, and 208, as well as the remaining steam generating tubes, is confined to a space 210 on the furnace side of the drum 202, this space being separated from the remainder of the drum by the plate baffle 212. The densifiers 200 receive the mixture of steam and water from the upper section of this space and separate the water and steam, the separated water being discharged through the outlets 214 under the water level in the drum 202 and the steam being vented by the outlets 220 to the steam space of the drum. This steam space is connected by supply tubes 222 to a superheater which is indicated in Fig. 9 of the drawings at 224.

In the boiler illustrated in Figs. 6 and 9, furnace gases pass from the furnace 230 across the steam generating tubes 208 in the first gas pass 232 and then around the rear edge of the baffle 234. The gases then pass forwardly over steam generating tubes 236 in the second gas pass 238. Beyond the tubes 236 the gases turn rearwardly of the baffle 240 and pass out of the boiler through the third gas pass 242.

What is claimed is:

1. In a water tube steam generator, a furnace, means forming a submerged water chamber, a plurality of upper steam and water drums, steam generating tubes connecting the water chamber to said drums and exposed to the heat of the furnace gases, wall cooling tubes associated with a wall of the furnace and arranged to discharge the steam and water mixture therefrom into one of said drums, whirl chamber densifying means within one of the drums and having direct connection with the wall cooling tubes so as to act upon the steam and water mixture discharged from the wall cooling tubes to separate the steam and water of said mixture, the densifying means having an outlet connection to discharge the separated water in a confined stream to a position beneath the water level of that drum, said densifying means discharging its separated steam directly into the steam space of said drum, downcomer tubes connecting the water space of a succeeding one of said drums with said water chamber, water circulators connecting the first of said drums to said succeeding drum, and crossover tubes so associated with the circulators and downcomers that water may flow directly to said downcomers from said first mentioned drum, means connecting the steam spaces of the drums, and steam offtake means arranged on one of the drums.

2. In a 3-drum steam generator of the bent tube type, a front upper drum, a rear upper drum, a steam outlet from the rear drum, means forming a lower water chamber, downcomers and steam generating tubes connecting said water chamber to said drums and extending across the path of furnace gases, steam circulators connecting the front and rear upper drums, means forming a circular whirl chamber of a steam and water separator disposed within the rear drum, means for conducting steam and water directly from the front drum to a tangentially arranged inlet of the whirl chamber, and a direct connection between a downcomer inlet and the water outlet of the whirl chamber conducting separated water in a confined stream from the whirl chamber to a downcomer, said whirl chamber being arranged with its steam outlet in direct communication with the steam space of the rear drum.

3. In a steam generator, a furnace, a plurality of upper drums, a lower drum, front and rearward banks of tubes connecting the lower drum to the upper drums and disposed in the path of the furnace gases, a rearward bank of tubes including downcomers, circulators connecting the upper drums, the front bank of tubes discharging steam and water mixtures into the front upper drum at high velocities by reason of the exposure of those tubes to furnace gases at high temperatures, means in a rearward upper drum directly connecting tubes of a rearward bank with circulators conducting steam and water mixtures from the front drum, kinetic steam and water separators in said connecting means, the separators having steam outlets communicating

with the steam space of the rearward drum, the separated water passes from the separators in confined streams to the connected downcomer tubes of the rearward bank, and a steam outlet in said rearward drum.

4. In a steam generator, a steam and water drum normally having a water level therein, a steam offtake leading from the steam space of the drum, means forming a cylindrically walled whirl chamber of a steam and water separator within the drum, said whirl chamber being disposed at least in part above said level, steam generating tubes, steam and water inlet means directing steam and water eccentrically or tangentially into the whirl chamber at high velocity in such a way as to set up a whirling action of all of the steam and water in the whirl chamber, fluid confining means establishing direct communication between the steam generating tubes and the steam and water inlet means, said whirl chamber having an interior wall which is unobstructed in line with the steam and water inlet and at least to a position beyond the steam and water inlet, means including a restricted and liquid sealed whirl chamber outlet providing for the discharge of the separated water in a confined stream, outlet means beginning centrally of the end of the whirl chamber whereby separated steam may pass to the steam space of the drum, and means connecting the water space of the drum to the inlets of the steam generating tubes, the whirl chamber and its outlet being constructed and arranged to cause water entering the chamber at the inlet to flow through the outlet with a velocity head sufficient at least to balance the static head of the water in the drum when the drum water level is higher than the level of the entrance of the outlet.

5. In a boiler having a steam and water drum and a plurality of steam generating tubes connected to said drum, a centrifugal steam and water separator inside the drum and comprising a whirl chamber, a tangential steam and water inlet toward one end of said chamber, fluid confining means establishing direct communication between the steam generating tubes and the whirl chamber inlet so that the whirl chamber receives the unseparated steam and water mixture from the steam generating tubes at substantially the pressure of the mixture leaving the tubes to cause a whirling of the fluid within said chamber, said whirl chamber having an interior wall which is unobstructed in line with the steam and water inlet and at least to a position beyond the steam and water inlet, a steam outlet at the end of said chamber nearest the inlet, and a restricted water outlet at the end of said chamber opposite the steam outlet end, constructed and arranged to cause water entering said chamber at said inlet to flow through said outlet with a velocity head sufficient at least to balance the static head of the water in the drum when the drum water level is higher than the level of the entrance to said outlet.

6. In a boiler having a steam and water drum and a plurality of steam generating tubes connected to said drum, a centrifugal steam and water separator inside the drum and comprising a whirl chamber, a tangential steam and water inlet toward one end of said chamber, fluid confining means establishing direct communication between the steam generating tubes and the whirl chamber inlet so that the whirl chamber receives the unseparated steam and water mixture from the steam generating tubes at sub-

stantially the pressure of the mixture leaving the tubes to cause a whirling of the fluid within said chamber, said whirl chamber having an interior wall which is unobstructed in line with the steam and water inlet and at least to a position beyond the steam and water inlet, a steam outlet at the end of said chamber nearest the inlet, and a restricted water outlet at the opposite end of said chamber, constructed and arranged to cause water entering said chamber at said inlet to flow through said outlet with a substantial continuation of the velocity of the water within said chamber.

7. In a steam generator, a steam and water drum normally having a water level therein, a steam offtake leading from the steam space of the drum, means forming a cylindrically walled whirl chamber of a steam and water separator within the drum, said whirl chamber being disposed at least in part above said level, steam generating tubes, steam and water inlet means directing steam and water eccentrically or tangentially into the whirl chamber at high velocity in such a way as to set up a whirling action of all of the steam and water in the whirl chamber, fluid confining means including a separate inlet compartment of the drum establishing direct communication between the steam generating tubes and the steam and water inlet means, said whirl chamber having an interior wall which is unobstructed in line with the steam and water inlet and at least to a position beyond the steam and water inlet, means including a restricted and liquid sealed whirl chamber outlet providing for the discharge of the separated water in a confined stream, outlet means beginning centrally of the end of the whirl chamber whereby separated steam may pass to the steam space of the drum, and means connecting the water space of the drum to the inlets of the steam generating tubes, the whirl chamber and its outlet being constructed and arranged to cause water entering the chamber at the inlet to flow through the outlet with a velocity head sufficient at least to balance the static head of the water in the drum when the drum water level is higher than the level of the entrance of the outlet, said inlet compartment communicating with said inlet means on one side and having the steam generating tubes discharging thereto at its opposite side.

8. In a boiler having a steam and water drum and a plurality of steam generating tubes connected to said drum, a centrifugal steam and water separator including a whirl chamber inside the drum, a tangential steam and water in-

let toward one end of said chamber, fluid confining means including a separate inlet compartment of the drum establishing direct communication between the steam generating tubes and the whirl chamber inlet so that the whirl chamber receives the unseparated steam and water mixture from the steam generating tubes at substantially the pressure of the mixture leaving the tubes to cause a whirling of the fluid within said chamber, said whirl chamber having an interior wall which is unobstructed in line with the steam and water inlet and at least to a position beyond the steam and water inlet, a steam outlet at the end of said chamber nearest the inlet, and a restricted water outlet at the opposite end of said chamber, constructed and arranged to cause water entering said chamber at said inlet to flow through said outlet with a velocity head sufficient at least to balance the static head of the water in the drum when the drum water level is higher than the level of the entrance to said outlet, said inlet compartment communicating with the outlets of the steam generating tubes and having direct connection with said whirl chamber inlet.

9. In a boiler having a steam and water drum and a plurality of steam generating tubes connected to said drum, a centrifugal steam and water separator including a whirl chamber inside the drum, a tangential steam and water inlet toward one end of said chamber, fluid confining means including a separate inlet compartment of the drum establishing direct communication between the steam generating tubes and the whirl chamber inlet so that the whirl chamber receives the unseparated steam and water mixture from the steam generating tubes at substantially the pressure of the mixture leaving the tubes to cause a whirling of the fluid within said chamber, said whirl chamber having an interior wall which is unobstructed in line with the steam and water inlet and at least to a position beyond the steam and water inlet, a steam outlet at the end of said chamber nearest the inlet, and a restricted water outlet at the opposite end of said chamber, constructed and arranged to cause water entering said chamber at said inlet to flow through said outlet with a substantial continuation of the velocity of the water within said chamber, said inlet compartment communicating with the outlets of the steam generating tubes and having direct communication with said whirl chamber inlet.

HOWARD J. KERR.
